United States Patent Office

Des. 202,975
Patented Nov. 23, 1965

202,975

PREFORMED NECK SCARF

Lee D. Miller and Lidia B. Miller, both of 310 W. 72nd St., New York 23, N.Y.

Filed Feb. 23, 1965, Ser. No. 83,928

Term of patent 14 years

(Cl. D3—16)

We claim:

The ornamental design for a preformed neck scarf, as shown.
